UNITED STATES PATENT OFFICE.

NATHAN SHURE, OF CHICAGO, ILLINOIS.

DESIGN FOR A TOY PEDESTAL.

44,187.

Specification for Design.

Patented June 10, 1913.

Application filed December 14, 1912. Serial No. 736,844. Term of patent 3½ years.

To all whom it may concern:

Be it known that I, NATHAN SHURE, a citizen of the United States, and residing at Chicago, in the county of Cook, State of Illinois, have invented a new and original Design for a Toy Pedestal, of which the following is a complete specification, reference being had to the accompanying drawing, forming part thereof.

The illustration is a side view of my new design showing a bird on top of an ornamental toy pedestal with a foot or base for said pedestal.

I claim:

The design of a toy pedestal as shown and described.

NATHAN SHURE.
